COMBINED ROSARY AND STATUETTE

Elsie Oppido, East Williston, N. Y.

Application February 6, 1958, Serial No. 49,523

Term of patent 14 years

(Cl. D29—23)

Figure 1 is a front elevational view of a combined rosary and statuette showing my new design; and Figure 2 is a side elevational view thereof.

The side not shown is the same in appearance as the side shown and the back is substantially plain and unornamented.

I claim:

The ornamental design for a combined rosary and statuette, substantially as shown and described.
